UNITED STATES PATENT OFFICE.

LOUIS JOSEPH HIRT, OF YONKERS, NEW YORK.

TURBINE CONSTRUCTION.

1,314,806.

Specification of Letters Patent.

Patented Sept. 2, 1919.

Application filed March 21, 1919. Serial No. 284,022.

To all whom it may concern:

Be it known that I, LOUIS JOSEPH HIRT, a citizen of the United States, residing at Yonkers, in the county of Westchester and 5 State of New York, have invented certain new and useful Improvements in Turbine Constructions, of which the following is a specification.

This invention relates to steam turbine 10 construction, its objects being to effect tight and durable seating of the buckets on the bucket-carrier disks, to minimize lateral deflection and vibration of the buckets when in use on their carrier disks, to minimize the 15 liability of the present frequent cracking of the peripheral margins of the carrier disks, and to cheapen the cost of manufacture of such turbines.

It is well known to all skilled in the art 20 that the bucket-carrier disks of steam turbines are subject continuously in use to expansion in some parts and almost instantaneous contraction in other parts, the expansions and contractions occurring with great 25 frequency and very often in rapid alternation. In addition to the usual centrifugal and tangential stresses, the bucket-carrier disks are subject to stresses in consequence of becoming heated by the steam and of 30 cooling; and when, for example, steam is shut off, the temperature of the buckets and of the peripheral marginal portion of the bucket-carrying disk becomes lower than the temperature of the disk nearer the hub so 35 that the peripheral marginal portion contracts more rapidly than the more expanded central portion of the disk, thus causing what is known in the art as hoop stresses with great frequency, causing crystallization 40 of the outward portion of the disk around its peripheral marginal portion and in then occasioning peripheral marginal cracking of the disk. It is also known in the art that the centrifugal tangential and 45 hoop stresses in a bucket-carrier disk have constant uniform temperature and when running at a high speed within the elastic limits of the material, is not so much subject to the stresses caused by the expansions 50 and contractions mentioned above; but in practice steam turbines are subject to variable station loads which automatically regulate the steam supply and thereby vary the heat to which the turbines are subject, with 55 consequent frequent cooling, and it is due to the frequent alternate expansions, con-

tractions and crystallization of the disks that they so frequently crack, occasioning delays, renewals and very considerable expense.

In the accompanying drawings forming a 60 part hereof and illustrating my invention,

Figure 1 is a side elevation of a bucket-carrier disk shown provided with diametrically opposed radial slots that severally extend from the periphery of the disk inwardly toward the hub, the slots being of equal length; with integral disk projections between the slots; and with a plurality of buckets seated on each disk projection.

Fig. 2 is a view partially in section and 70 partially in elevation at line 2—2 of Fig. 1, and shows one of the buckets interlockingly seated on the bucket-carrier disk and bonded thereto by welded metal.

Fig. 3 is a cross-sectional detail of one of 75 the buckets at line 3—3 of Fig. 2; and

Fig. 4 is a view showing the interlocking members of a bucket and carrier disk spaced apart for convenience in lettering the interlocking members.

In the drawings, the carrier disk 1 is formed with an integral marginal flange 2 extending wholly around the disk and the periphery of which is indicated by 3. The inward face of this disk is formed with a 85 circular groove 4 radially inward of and spaced apart from the periphery 3 with which the radially outward and inward walls of the groove 4 are concentric, thus forming on the inward face of the flange 90 an annular rib 5 the periphery of which is a part of the periphery of the flange. The inward face of the rib 5 is about in line with a plane projected diametrically through the disk midway between its sides. The outer 95 peripheral corner of the carrier disk flange is beveled inwardly and outwardly at 6. The inward wall of the groove 4 is indicated by 7 and extends from the base of the flange toward the opposite side of the disk and to its junction with the inward and outward beveled wall 8. Thus the carrier disk is formed with two peripheral bucket-shank-seating walls 3 and 7 of unequal diameters and with the intermediate 100 annular rib 5 and the circular groove 4.

The shank 9 of each bucket is reduced in lateral thickness and formed on one side with an arcuate groove 10 to receive and interlock with an arced portion of the disk rib 5; and with an arcuate rib 11 to fit in and interlock with an arced portion of the 110

disk groove 4; and with an arcuate bottom wall 12 to fit on the peripheral wall of the carrier disk. The lateral bottom wall of the arcuate groove 10 is deep enough to receive the rib 5. The outward arced wall of the groove 10 overlaps and bears on the peripheral wall 3 of the carrier disk. The inward arcuate end of the shank 9 is downwardly and inwardly beveled at 13 and on the opposite side of the shank its side wall is inwardly beveled at 14.

In the assemblage indicated and described, the beveled walls 6 and 14 on one side and the beveled walls 8 and 13 on the other side form arcuate V-shaped spaces wherein metal 15 is welded in order to bond the bucket shanks in place on the disk carrier.

The buckets are by the described means not only seated tightly in place on the carrier disk, but are seated in such a manner that they will not become loose.

In accordance with an important feature of this invention the carrier disk is provided with a series of approximately 25 radially disposed thin slots 16 all of equal length and spaced apart one from another, and severally extending from the periphery of the disk inwardly toward the hub, and inwardly beyond the lower ends of the 30 bucket shanks, thus forming the peripheral marginal portion of the disk with a series of integral endwise separated disk projections 17 on which I may mount any number of buckets in the way above described 35 or otherwise. For perfectly balancing the disk and buckets, the slots are formed at equal distances apart, and at each side of the axis of the disk two of the slots are diametrically opposed one to the other. The 40 number of the slots 16 and bucket-carrying projections 17 may be varied, but such slots and projections will be of even numbers from two upwardly. In the drawings I show sixteen with six buckets anchored

on each bucket-carrying projection 17. By 45 this construction the several bucket-carrying projections are free to expand and contract one independently of another, whereby there are minimized in the disk the tangential stresses due to the expansion and 50 contraction of the disks at their peripheral margins, their peripheral margins becoming subject only, or approximately only, to radial stresses.

What I claim is,—

1. The combination of a turbine bucket-carrier disk and a series of thereon radially mounted buckets, the disk being formed with a peripheral integral flange having on its inward face an annular rib and an adjacent annular groove, and each bucket shank being formed with an arcuate groove and an adjacent arcuate rib, the flange rib being entrant in the arcuate groove of the bucket shank, and the arcuate rib of the 60 bucket shank being entrant in the flange groove; and the bucket shank being formed with two arcuate end walls one of which is seated on the periphery of the disk and the other of which is seated on the radial inward wall of the groove in the disk; the so-seated bucket shank being on each opposite side welded to the disk; and the bucket-carrier disk being slotted from its periphery 65 inward to form separated integral bucket-carrying projections of the disk.

2. The combination in a turbine, with a bucket-carrier disk provided with a series of slots extending inwardly from the periphery of the disk and forming a series of 80 bucket-carrying integral projections spaced apart one from another and severally free to expand and contract, of a bucket fixed on each projection.

In testimony whereof I have hereunto 85 set my hand this 18th day of March, 1919.

LOUIS JOSEPH HIRT.
